US00D599477S

(12) **United States Design Patent**
Hood et al.

(10) **Patent No.:** **US D599,477 S**
(45) **Date of Patent:** **** Sep. 1, 2009**

(54) **SANITARY TOWEL**

(75) Inventors: **Lisa June Hood**, Cincinnati, OH (US);
Federica Denti, Schwalbach am Taunus
(DE); **Christine Dodge**, Liberty
Township, OH (US); **Signe Christina
Larson**, Cincinnati, OH (US)

(73) Assignee: **The Procter & Gamble Company**,
Cincinnati, OH (US)

(**) Term: **14 Years**

(21) Appl. No.: **29/331,247**

(22) Filed: **Jan. 22, 2009**

(51) **LOC (9) Cl.** **24-04**

(52) **U.S. Cl.** **D24/124; D24/125**

(58) **Field of Classification Search** **D24/124-125;**
